UNITED STATES PATENT OFFICE.

ALVA M. RICKS, OF LOS ANGELES, CALIFORNIA.

BEET-TOPPING MACHINE.

Application filed June 12, 1920. Serial No. 388,689.

To all whom it may concern:

Be it known that I, ALVA M. RICKS, a citizen of the United States, residing at Los Angeles, in the county of Los Angeles, State 5 of California, have invented new and useful Improvements in Beet-Topping Machines, of which the following is a specification.

This invention relates to machines for topping beets, or the like, and it is an object 10 of the present invention to provide a machine of this character which will operate effectively, efficiently and uniformly.

The subject of this application is particularly that of the beet topping means herein- 15 after described, the beet digging means, and the beet handling means which I hereinafter describe, being the subject matter of my co-pending application entitled "Beet digging and conveying machine," filed June 26, 1920, 20 Serial No. 392,053, wherein they are fully set forth and are claimed.

Among the features of the invention may be mentioned the cutters provided for cutting the tops from the beets, the fingers provided for engaging and moving the beets while they are being cut, the general arrangement and combinations of parts, etc.

The various objects and features of the invention will be best and more fully understood from the following description of a typical preferred form of the invention throughout which reference is had to the accompanying drawings, in which:

Fig. 1 is a side elevation of my improved 35 machine showing it in its raised position; Fig. 2 is a plan view of the same being a view taken as indicated by line 2-2 on Fig. 1; Fig. 3 is an enlarged side elevation of the operating portion of the machine showing it 40 in its down or operating position; Fig. 4 is a reduced sectional view taken as indicated by line 4-4 on Fig. 3 showing the various driving connections; Fig. 5 is a reduced 45 sectional view taken as indicated by line 5-5 on Fig. 3; Fig. 6 is a plan view of the upper or rear parts shown in Fig. 3; Fig. 7 is an enlarged sectional view taken as indicated by line 7-7 on Fig. 3, showing the topping knives; Fig. 8 is an enlarged rear 50 end view of the topping mechanism as indicated by line 8-8 on Fig. 3; and Fig. 9 is an enlarged sectional view taken as indicated by line 9-9 on Fig. 1.

For simplicity and sake of clearness the 55 leaves or foliage of the beets will be termed tops while the bodies will be termed beets.

In the drawings I show a suitable main frame 10 supported at its forward end by a pair of wheels 12 and at its rear end by a pair of wheels 11. In the specific form of 60 construction herein set forth the machine is arranged to be propelled by an engine 29 through the rear wheels 11. The engine 29, which is preferably an ordinary internal combustion engine mounted on frame 10, is 65 connected with the wheels 11 through a transmission, or change-speed mechanism, 29^a and a differential mechanism 29^b, such as is common in automobile construction. A suitable clutch 29^c is arranged between the 70 engine and the transmission so that the machine can be conveniently controlled. The shaft 30 which extends from the differential mechanism has drive pinions 31 mounted on it to engage internal gears 32 arranged with- 75 in the rims of wheels 11.

Within the main frame 10 is mounted a sub-frame 13 which carries beet digging, conveying, and topping mechanisms. This sub-frame 13 is pivotally connected at its 80 rear end to the main frame 10 by a horizontal transverse shaft 14, which extends across the main frame 10 and through the sub-frame 13. The shaft 14 is rotatably carried between main frame members 15 and ex- 85 tends through hangers, or bearings, mounted on the sub-frame 13. By this construction the sub-frame 13 is vertically adjustable, that is, it may be swung or adjusted about the shaft 14 as an axis. For adjusting the 90 sub-frame 13 racks 16 are mounted on the forward end of sub-frame 13 to extend upwardly and engage pinions 17 mounted on a horizontal transverse shaft 18. The shaft 18 is carried in suitable bearings 18^a 95 and has a hand wheel 19 mounted on one of its ends in order that it may be conveniently rotated by hand. It will be readily understood how rotation of shaft 18 will cause lowering or raising of 100 racks 19 through pinions 17. To afford a locking means for this adjusting arrangement pawls 20 are mounted on shaft 21 and are arranged to normally be held in engagement with pinions 17 by springs 22. To re- 105 lease the locking mechanism pawls 20 are released from pinions 17 by pressure on their rear ends.

The sub-frame 13, as before stated, carries beet digging, conveying and topping mecha- 110 nisms. The beet digging mechanism comprises, generally, a soil engaging and dis-

turing member 113 adjustably mounted on the main frame 10, and a pair of bits 124 mounted on the forward part of the frame 13 and adapted to cooperate with said member 113 to pull and lift the beets. The conveying mechanism extends from the bits rearwardly to the topping mechanism, arranged at the rear of the sub-frame, and comprises, generally, a first conveyer mechanism 10 which extends from the bits to a second conveyor extending from the main conveyer to the topping mechanism. The entire beet handling mechanism is arranged so that it is compact and so that the bits 124 can be lowered to the ground, by lowering sub-frame 13 in the manner above set forth, so that they will engage and pick up the tops of the beets. In the operation of the machine the various elements and mechanisms above 15 referred to co-operate in a manner which makes the machine positive, accurate, and efficient in its operation.

When the tops reach a pre-determined point near the upper or inner ends of the 20 conveyer rolls 23 they are transferred from the first conveying mechanism to conveying chains 24. To transfer the beets, from the first conveyer mechanism to the conveyer chains 24, without allowing them to drop, 25 a guide finger 10^a is arranged to extend partially between the conveyer rolls 23 from their undersides. The finger 10^a is arranged a little to one side so that it will not interfere with the advancing fingers 60 and is 30 arranged to engage the top portions of the beets to prevent further upward movement of the beets and thereby cause the tops to be withdrawn from between the conveyer rolls 23. It is preferred that the finger 10^a 35 be somewhat curved, as shown in the drawings, so that the tops will be gradually withdrawn from the rolls 23. In practice when the machine is operating the conveyer rolls 23 are at an angle of about 45 degrees relative to the ground while the guide finger 10^a is arranged to be substantially horizontal. The arrangement of conveyer rolls and the guide finger and the shape of the guide finger cause the tops to be removed from 40 the rolls 23 gradually rather than suddenly. This is important in that it prevents the tops from being torn or stripped from the beets and prevents jarring or sudden shocks that might cause the beets to be dislodged 45 from the machine. The guide finger 10^a may be mounted on the sub-frame 13 in any suitable manner. For instance, it may be formed with arms 10^b which are secured to a horizontal frame member 91, arranged to 50 extend rearwardly from the braces 66, as clearly shown in Fig. 3.

The conveyer chains 24, which receive the tops from the guide finger 10^a, are arranged horizontally and their forward portions are 55 sufficiently close to the conveyer rolls 23 that

the tops are still in engagement with, or gripped by, the conveyer rolls 23 when they are caught by the chains 24. The fact that the tops are not completely removed from the conveyer rolls 23 before they are caught 60 by the chains prevents them from being dropped during the transfer from the rolls to the chains. Each of the conveyer chains 24 is carried by a sprocket 24^a, a sprocket 24^b, and a sprocket 24^c. The sprockets 24^b 65 are mounted on vertical driven shafts 94 while the sprockets 24^a and 24^c are mounted on vertical shafts 99 and 94^a respectively. The shafts 94 are at the sides of the machine, or at the sides of the sub-frame 13, 70 in order that they may extend from the upper portion of the sub-frame to the lower portion, where the topping mechanism is arranged, without interfering with the conveyer rolls 23. The several sprockets which 75 carry the chains 24 are arranged so that the chains have parallel rearwardly moving portions arranged together to grip the tops and carry them rearwardly. Shafts 94 are rotated in opposite directions and at the 80 same speed so as to cause the parallel portions of chains 24 to both move rearwardly at the same speed. It will be readily understood how tops, delivered to the chains 24 from conveyer rolls 23 by guide finger 10^a 85 are firmly held, or gripped, between the chains 24 and are advanced or moved rearwardly carrying with them the beets.

The chains 24 in carrying the beets rearwardly carry them into engagement with 90 cutters or knives 25, arranged close under the chains 24, and thereby cause the beets to be cut or removed from the tops. In the particular form of mechanism herein shown the knives 25 are in the form of disks and 95 are mounted on vertical shafts 104 which are driven from shafts 99 through chains 102 running over sprockets 201 and 202 mounted on the shafts 99 and 104, respectively. The various parts in connection 100 with the drives for the knives are so proportioned that the peripheral speed of the knives is a little faster than the speed of the chains 24. The knives or cutters 25 are 105 preferably sufficiently large to slightly overlap thereby causing the tops to be positively and cleanly cut from the beets. The knives 25 are mounted on shafts 104 so as to be vertically adjustable thereby making it possible 110 to set them in various positions so that they 115 will cut the tops from the beet at the desired points.

To hold the beets as well as the tops while the tops are being cut fingers 11^a are arranged to extend radially from the shafts 125 104 below the knives 25 to engage the beets. The fingers 11^a upon engaging the beets positively move them rearwardly and brace them while the tops are being cut. The fingers 11^a are mounted on collars 11^b adjust- 130

ably mounted on the lower ends of shafts 104.

When the beets have been cut from the tops the beets drop onto a conveyer 106 and are carried out of the machine. The conveyer 106 may comprise an endless belt and may be driven in any suitable manner. For instance, it may be driven by bevel gear 107, mounted on the lower end of one of the driven shafts 94, engaging bevel gear 108, mounted on the shaft 109 over which the belt runs. The tops after being cut from the beets are carried by the chains 24 beyond the knives 25 and are released when the chain starts to pass around the sprocket 24^a. The tops drop into a box 110 having a hinged bottom 111 supported by a suitable spring 112. When the weight of tops in box 110 is sufficient to overcome the tension of spring 112 the bottom box 111 drops or swings downwardly allowing the tops to fall to the ground in piles.

Having set forth the various parts and mechanisms which operate, or act upon, the beets from the time that they are removed from the ground until they are topped and removed from the machine, I will now proceed to set forth a form of drive mechanism that may be employed to operate, or drive, the above mechanisms and parts. For instance, as shown in the machine herein disclosed, the entire mechanism may be operated from shaft 30 through a chain 34 which runs over a sprocket 33 mounted on shaft 30 and a sprocket 35 mounted on shaft 36. The shaft 36 is a horizontal transverse shaft mounted on main frame 10 and carries a sprocket 38 which carries a chain 39 arranged on a sprocket 40 mounted on shaft 14. This manner of driving the shaft 14 from the shaft 30 causes it to rotate in a counter-clockwise direction, as indicated by the arrows throughout the drawings. The shaft 14 has mounted on it two oppositely faced bevel gears 85 which mesh with and drive bevel gears 86 mounted on shafts 87 which are carried in suitable bearings 28^a. The arrangement of bevel gears 85 and 86 causes the shafts 87 to rotate in opposite directions, as indicated by the arrows in the drawings. Sprockets 88 are mounted on the shafts 87 to carry and drive chains 89 which are arranged over sprockets 90 mounted on the spindles 23^a which extend from the rear ends of rolls 23 through mounting bracket 28, as clearly shown in Fig. 7 of the drawings. This driving mechanism comprises the drive for rolls 23 and causes them to rotate at the same speed and in opposite directions and so that their adjacent sides move upwardly.

To drive the chain 72 which carries the fingers 73 a shaft 44 is driven from shaft 14 through chain 42 running over sprocket 41, mounted on shaft 14, and sprocket 43,

mounted on shaft 44. The shaft 44 has mounted on it a gear 47 which meshes with and drives a gear 48 on a shaft 49. The gear connection between the shaft 44 and shaft 49 causes the shaft 49 to rotate in the proper direction and in a direction opposite to that in which shaft 44 rotates. A sprocket 50 is mounted on shaft 49 and carries a chain 51 which runs over a sprocket 52 mounted on shaft 53 thereby causing shaft 53 to rotate in the same direction as shaft 49. The shaft 77, on which is mounted sprocket 74 which carries chain 72, is driven from shaft 53 through a chain 83 carried on a sprocket 84 mounted on shaft 53 and a sprocket 82 mounted on shaft 77, as clearly shown in Fig. 5 of the drawings.

To drive the chain 59 on which the fingers 60 are mounted a shaft 58 is rotated from shaft 53 through chain 56 which runs over sprocket 55, mounted on shaft 53, and sprocket 57, mounted on shaft 58. The shaft 58 drives shaft 61, on which is mounted sprocket 60^a, through bevel gears 70 and 71 mounted on the shaft 58 and shaft 61 respectively.

The shafts 94, which drive conveyer chains 24, knives 25, and the conveyer 106, are driven from shaft 77 through bevel gears 205 and 206 mounted on shafts 77 and 94 respectively. It will be noted from the above description that the entire beet handling mechanism is driven from, or through, shaft 14. By thus driving the entire mechanism through shaft 14 and by arranging the sub-frame 13 to be pivotally mounted on shaft 14, the sub-frame can be adjusted or swung to any desired position without in any way affecting or changing any of the drives or drive mechanism.

Guide or support plates 210 are provided so to prevent the chains 24 from spreading which would result in the beets falling from the machine. Plates 210 are arranged parallel to the chains 24.

Having described a preferred form of my invention, I claim:

1. In a machine of the character described a cutter, means for holding beets by their tops and moving them into engagement with the cutter, means for engaging the bodies of the beets and co-operating with the first mentioned means in moving the beets while they are in engagement with the cutter, and an adjustable mounting for the means for engaging the bodies of the beets whereby it can be adjusted relative to the other parts.

2. In a machine of the character described, a pair of rotating cutters, a conveyer arranged to hold beets by their tops and move them into engagement with the cutters, and fingers moved to engage the bodies of the beets and co-operate with the

- conveyer in moving the beets while they are in engagement with the cutter.
3. In a machine of the character described, a pair of overlapping rotating cutters, a pair of chains having parallel portions moving in the same direction and adapted to carry beets by their tops into engagement with the cutters, and fingers operated with the cutters to engage the bodies of the beets and co-operate with the chains in moving the beets while they are in engagement with the cutters.
4. In a machine of the character described two oppositely rotating shafts, two cutters one mounted on each shaft, conveying means adapted to hold beets by their tops and move them into engagement with the cutters, and fingers arranged on one of the shafts to engage the bodies of the beets and co-operate with the conveying means in moving the beets while they are in engagement with the cutters.
5. In combination with a beet conveying apparatus, means for holding beets by their tops and carrying them, means for removing the beets from the conveying apparatus and directing them to the holding and carrying means, a cutter arranged to engage the beets while they are being held and carried by their tops, and means for engaging the bodies of the beets and co-operating with the holding and carrying means in moving the beets while they are in engagement with the cutter.
6. In combination with a beet topping cutter mounted on a rotating shaft, fingers mounted on the shaft to engage the beets while they are in engagement with the cutter.
7. In combination with a beet topping cutter adjustably mounted on a rotating shaft, fingers adjustably mounted on the shaft to be moved into engagement with the beets while they are in engagement with the cutter.
8. In a machine of the character described, comprising beet conveying apparatus, two parallel oppositely rotating shafts, cutters adjustably mounted on the shafts to overlap, conveyer chains having parallel adjacent portions moving together and in the same direction and adapted to hold and carry beets by their tops so that they are cut by the cutters, means for guiding the parallel portions of the chains, means for transferring the beets from the conveying apparatus to the chains, and fingers adjustably mounted on the shafts to engage the bodies of the beets and co-operate with the chains in moving the beets while they are in engagement with the cutters.
9. In a machine of the character described, a pair of overlapping rotating cutters, a chain conveyer adapted to carry beets by their tops into engagement with the cutters, and fingers operating to engage and move the beets while they are at the cutters.
10. In a machine of the character described two oppositely rotating shafts, two cutters one mounted on each shaft, conveying means adapted to hold beets by their tops and move them into engagement with the cutters, and fingers arranged on each of the shafts to engage the bodies of the beets and co-operate with the conveying means in moving the beets while they are in engagement with the cutters.
11. In a machine of the character described, two rotating shafts, cutters mounted on the shafts to cooperate in topping beets, and fingers extending from one of the shafts to engage beets while at the cutters.
12. In a machine of the character described, means for holding and moving beets by their tops, two rotating shafts, cutters mounted on the shafts to overlap and co-operate to top beets held by said means, and fingers extending radially from said shafts to engage the beets while at their cutters.

In witness that I claim the foregoing I have hereunto subscribed my name this 5th day of June 1920.

ALVA M. RICKS.

Witness:

VIRGINIA BERINGER.
